UNITED STATES PATENT OFFICE.

EDWARD RAWSON, OF MOSCOW, IDAHO.

PLANER.

SPECIFICATION forming part of Letters Patent No. 757,963, dated April 19, 1904.

Application filed May 21, 1903. Serial No. 158,117. (No model.)

To all whom it may concern:

Be it known that I, EDWARD RAWSON, a citizen of the United States, and a resident of Moscow, in the county of Latah and State of Idaho, have invented a new and Improved Planer, of which the following is a full, clear, and exact description.

The invention relates to woodworking machinery; and its object is to provide a new and improved planer arranged to permit a slow or fast feed of the material to be treated in either a forward or backward direction and to allow convenient adjustment of the feed-rolls and the cutter-head to treat materials of different thicknesses without stopping the machine.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a sectional plan view of the same on the line 2 2 of Fig. 3. Fig. 3 is a transverse section of the same on the line 3 3 of Fig. 2. Fig. 4 is an enlarged rear longitudinal sectional elevation on the line 4 4 of Fig. 2. Fig. 5 is an enlarged plan view, partly in section, of the reversing and speed-changing mechanism for the lower feed-rollers. Fig. 6 is an end elevation of the same, and Fig. 7 is a sectional plan view of the device for raising and lowering the cutter-head and upper feed-rolls.

The planer is mounted on a suitably-constructed bed A, supporting a feed-table B, through which extend transverse lower driven feed-rolls C, journaled in suitable bearings on the sides of the bed A and operating in conjunction with upper feed-rolls D, journaled in spring-pressed bearings E, held to slide vertically in guideways E', formed on a frame F, mounted to slide up and down in guideways A', arranged on the sides of the bed A, as plainly shown in the drawings. The feed-rolls C and D are arranged in pairs, and pref-

erably two pairs are located on one side of a transverse cutter-head G, and two other pairs are located on the opposite side of the said cutter-head. The shaft G' of the cutter-head G is journaled in suitable bearings arranged on the frame F, and on the said cutter-head shaft G' is secured a pulley G², connected by a belt G³ with a pulley G⁴, fastened on the main driving-shaft H, journaled in suitable bearings on the front end of the machine.

On the main shaft H are secured fast and loose pulleys H', connected by belt with other machinery to impart a rotary motion to the shaft H, which by the pulley G⁴, belt G³, and pulley G² imparts a rotary motion to the cutter-head G, so as to plane the material fed under the cutter-head by the pairs of feed-rolls C and D. A belt-tightener G⁵ is connected with the belt G³, so as to give the necessary tension to the belt on adjusting the frame F up and down to bring the rolls D and the cutter-head G in a proper relation to materials of different thicknesses.

In order to adjust the frame F, carrying the upper feed-rolls D, and the cutter-head G vertically, the following device is provided: The top cross-bar F' of the frame F extends in vertical guideways A² on the standards A³, forming part of the bed A, and in the said cross-bar F' screw vertically-disposed screw-rods F², mounted to turn in a top cross-beam A⁴, connecting the upper ends of the standards A³ with each other. On the upper ends of the cross-rods F² are secured bevel gear-wheels F³, in mesh with bevel gear-wheels F⁴, fastened on a transverse shaft F⁵, journaled in suitable bearings attached to the top cross-beam A⁴. On the inner end of the shaft F⁵ is secured a bevel gear-wheel F⁶, in mesh with a bevel gear-wheel F⁷, secured on the upper end of a shaft I, journaled at its upper end in a bearing A⁵, attached to one of the standards A³. On the shaft I is secured a spur-wheel I', in mesh with a spur-wheel I², secured on a shaft I³, journaled at its upper end in a bearing A⁶, secured to the inner face of one of the sides of the bed A, as plainly indicated in Fig. 3. (See also Fig. 7.) The lower ends of the shafts I and I³ carry bevel friction-wheels I⁴ and I⁵, adapt-

ed to mesh with corresponding friction-wheels I^6 and I^7 or with a double-bevel friction-wheel I^8 , according to the direction in which the lower ends of the shafts I and I^3 are moving—
 5 that is, when moved apart the wheels I^4 and I^5 move in mesh with the wheels I^6 and I^7 , and when the shafts are moved toward each other then the wheels I^4 and I^5 move simultaneously in mesh with the double wheel I^8 . The bevel
 10 friction-wheels I^6 , I^7 , and I^8 are secured on a transverse shaft I^9 , journaled in suitable bearings carried on the bed A , and on the said shaft I^9 is secured a pulley I^{10} , connected by a belt I^{11} with a pulley I^{12} , secured on the main
 15 shaft H . Now when the latter is rotated the said pulleys I^{12} and I^{10} and the belt I^{11} impart a rotary motion to the shaft I^9 , which by either of the friction-wheels I^6 or I^7 or the double wheel I^8 imparts a rotary motion to the
 20 wheels I^4 and I^5 in either a forward or backward direction, and consequently the shaft I is rotated either forwardly or backwardly, and a like motion is given to the shaft F^6 , which by the bevel gear-wheels F^4 and F^3 rotates
 25 the screw-rods F^2 to move the frame F up or down, according to the position of the wheels I^4 and I^5 relative to the wheels I^6 , I^7 and I^8 . It is understood that the shafts I and I^3 are mounted sufficiently loose in their bearings
 30 so that the lower ends of the shafts can be swung toward or from each other for the purpose above described. The lower ends of the shafts I and I^3 are engaged by bearings J and J' , formed on arms J^2 and J^3 , fulcrumed at
 35 J^4 on the bed A and pivotally connected at their free ends by links J^5 and J^6 with a disk J^7 , mounted to turn on the bed A and connected by an arm J^8 and link J^9 with a hand-lever J^{10} , fulcrumed on one side of the bed A and
 40 under the control of the operator. Now by swinging the hand-lever J^{10} in the direction of the arrow a' , as indicated in Fig. 1, the links J^5 and J^6 swing the arms J^2 and J^3 apart to move the friction-wheels I^4 and I^5 in mesh
 45 with the friction-wheels I^6 and I^7 to rotate the shaft I in one direction for moving the frame F upward, and with it the cutter-head G and the upper feed-rolls D . When the operator swings the lever J^{10} in the inverse direction of
 50 the arrow a' , then the turning of the disk J^7 causes the links J^5 and J^6 to swing the arms J^2 and J^3 toward each other to move the friction-wheels I^4 and I^5 simultaneously in mesh with the double friction-wheel I^8 , so that the
 55 shaft I is rotated in an opposite direction, and the frame F is caused to slide downward by the action of the screw-rods F^2 , as previously mentioned. It is understood that the lever J^{10} normally stands in a vertical position, and
 60 the wheels I^4 , I^5 then stand in an intermediate non-contacting position relative to the wheels I^6 , I^7 , and I^8 , and hence their continuous rotation does not affect the position of the frame F and the parts carried thereby unless the op-

erator moves the hand-lever J^{10} either to the right or left, as above described. On the frame F is arranged a pointer F^8 , (see Fig. 1,) indicating on a linear graduation F^9 , formed on one of the standards A^3 , to indicate the exact distance the lower end of the cutter-head G is from the table B . Thus by the operator simply manipulating the lever J^{10} as described and watching the movement of the pointer F^8 on the graduation F^9 he is enabled to quickly set the cutter-head G and the upper feed-rolls 75 D to the proper position, according to the thickness of the material to be treated. It will also be seen that this adjustment is carried out while the machine is running. In order to securely lock the frame F in position 80 after the desired adjustment thereof is made, the operator screws up a wheel-nut F^{11} on the threaded end of a rod F^{10} , connecting the sides of the frame F with each other, as plainly shown in Figs. 1 and 3. 85

The lower feed-rolls C are driven from the main shaft H , and in order to rotate the said feed-rolls C in either a forward or backward direction and at a high or a low rate of speed to permit a slow or fast feed of the material 90 to be treated in either a forward or backward direction the following device is provided: A transverse shaft K is journaled in suitable bearings on the bed A and is provided at its inner end with a sprocket-wheel L , connected by a sprocket-chain L' with a sprocket-wheel L^2 , secured on the shaft of the first feed-roll C , which latter is connected by sprocket-wheels and sprocket-chain with the next feed-roll C , and in a like manner the several feed-rolls are connected with each other, so that when the first feed-roll is driven from the shaft K the other feed-rolls rotate in unison with the same at the same speed and in the same direction. (See Figs. 2 and 4.) On the outer end 100 of the shaft K is secured a double bevel gear-wheel K' , in mesh with pinions N and N' , secured on longitudinally-extending shafts N^2 and N^3 , journaled in suitable bearings on the bed A . (See Figs. 1, 2, and 5.) On the forward ends of the shafts N^2 and N^3 are mounted to turn with and to slide on the same friction-pulleys N^4 and N^5 , of which the pulley N^4 extends between disks O and O' and the pulley N^5 extends between disks O' and O^2 , the said disks O , O' , and O^2 being secured on the main shaft H . The pulleys N^4 and N^5 are adapted to be moved inward or outward in a radial direction relative to the disks O , O' , and O^2 , so as to transmit the speed of the disks at a lower or higher rate of speed, according to the position which the pulleys N^4 and N^5 occupy inwardly or outwardly on the said disks. The pulleys N^4 and N^5 are adapted to be shifted on their shafts N^2 and N^3 by shifting-forks P , engaging annular recesses on the hubs of the said pulleys N^4 and N^5 , and the said shifting-forks P are pivotally connected with cross- 115 120 125

heads P', sliding loosely on the shafts N² N³, and the cross-heads P' are connected by links P² with a hand-lever Q under the control of the operator and fulcrumed at its lower end 5 on the bed A. On the hand-lever Q is arranged a locking-lever Q', adapted to engage a notched segment Q² for locking the lever Q in a desired position. Now by the operator swinging the lever Q in the direction of the arrow b' the shifting-forks P are moved rearwardly to move the pulleys N⁴ N⁵ outwardly relatively to the disks, and when the operator swings the lever in the inverse direction of the arrow b' then the pulleys N⁴ N⁵ are moved 10 inwardly on the disks toward the shaft H, carrying the disks. The shafts N² and N³ adjacent to the bevel gear-wheels N and N' are journaled in a bearing N⁶, fixed to the frame A, and the outer ends of the said shafts N² N³ are journaled 15 in arms R R', fulcrumed at their lower ends at R² on a bracket attached to the bed A. The upper ends of the arms R and R' are connected by links R³ R⁴ with a disk R⁵, journaled on the bracket attached to the bed A (see 20 Figs. 1 and 6,) and on the said disk is secured a handle R⁶, under the control of the operator and provided with a locking-lever R⁷, adapted to engage a notched segment R⁸, carried by the said bracket. Now by the operator swinging 25 the hand-lever R⁶ transversely in the direction of the arrow c' the disk R⁵ is turned so as to cause the links R³ R⁴ to swing the arms R and R' toward each other, so that the forward ends of the shafts N² and N³ are swung 30 in a like direction to move the pulleys N⁴ and N⁵ simultaneously in frictional contact with the opposite faces of the middle disk O', and when the handle R⁶ is moved in the inverse direction of the arrow c' then the arms 35 R and R' are caused to swing apart, so that a like movement is given to the outer ends of the shafts N² and N³, and the pulleys N⁴ N⁵ are thus moved in frictional contact with the disks O and O². (See Figs. 2 and 5.) Now 40 when the pulleys N⁴ and N⁵ are in frictional contact with the disks O and O², as previously explained, then the shaft K is rotated in one direction, and with it the lower feed-rolls C, to move the material fed between the pairs of 45 feed-rolls C and D in the direction of the arrow d', and when the pulleys N⁴ and N⁵ are in mesh with the middle disk O' then the shaft K is rotated in an opposite direction, and with it the feed-rolls C, so that the material is 50 moved in the inverse direction of the arrow d' over the table B. Now the speed with which the shaft K and the feed-rolls C are rotated depends on the inward or outward position of the pulleys N⁴ N⁵ on the disks O, O', and O², with which they are engaged at the time—that is, when the pulleys N⁴ and N⁵ are in an innermost position. Then a slower rotary movement is transmitted by the disks to the 55 said pulleys, and consequently to the shafts N², N³, and K and the feed-rolls, and when the pulleys N⁴ and N⁵ are in an outermost position on the said disks then a faster rotary motion is given to the feed-rolls. 60

On the feed-table B adjacent to the cutter-head G is arranged a longitudinally-extending guide S for the material to abut on while passing over the feed-table under the cutter-head G, and opposite this guide S is arranged a side cutter-head T, secured on the upper end of a vertically-disposed shaft T', extending 70 through a transverse slot B', formed in the feed-table B to allow moving this cutter-head T transversely nearer to or farther from the guide S, according to the width of the material under treatment. The cutter-head T has its shaft T' journaled in a bearing T², (see Fig. 3,) mounted to slide transversely on a guideway T³, secured to the under side of the feed-table B. The bearing T² is adapted to be fastened on the guideway T³ by a suitable set-screw T⁴ after the cutter-head is adjusted relative to the width of the material under treatment, as above described. On the lower end of the shaft T' is secured a pulley T⁵, connected by a cross-belt T⁶ with a drum T⁷, secured on the main shaft H, so that when the latter is rotated the drum T⁷, belt T⁶, and pulley T⁵ impart a rotary motion to the cutter-head T to trim one edge of the material to give the latter the desired width, it being understood 80 that the other edge of the material rests on the guide S. 85

The operation is as follows: When the several parts are in the position illustrated in the drawings and the main shaft H is rotated, then the material fed on the table B in the direction of the arrow d' is moved forward by the pairs of feed-rolls C and D and carried under the cutter-head G for the latter to cut the face thereof to the thickness to which the machine is set. The side cutter-head T trims the outer edge of the material as the same passes rearwardly under the rearmost pair of feed-rolls C and D. Now when it is desired to increase or decrease the speed with which the feed-rolls feed the material forward then the operator simply manipulates the lever Q correspondingly to shift the friction-pulleys N⁴ and N⁵ lengthwise on their shafts N² N³ to move the said friction-pulleys in contact with the corresponding friction-disks nearer to or farther from the axis of the said disks. When it is desired to run the material backward, then the operator actuates the handle R⁶, as previously described, so as to move the friction-pulleys N⁴ and N⁵ in contact with the middle disk O' to cause a reversing of the motion of the lower feed-rolls C to run the material in the inverse direction of the arrow d'. For changing the position of the cutter-head G and the upper feed-rolls D for treating thinner or thicker material the operator manipulates the lever J¹⁰, as previously de- 90 95 100 105 110 115 120 125

scribed, to move the frame F up or down to adjust the cutter-head G and the feed-rolls D relative to the table, according to the thickness of the material under treatment.

5. Having thus described my invention, I claim as new and desire to secure by Letters Patent—

1. A planer provided with a bed, a frame vertically slideable thereon and carrying upper feed-rolls and a cutter-head, lower feed-rolls journaled in the said bed, a main shaft 10 connected with the said cutter-head and the said lower feed-rolls, to rotate the same, and means for raising and lowering the said frame, the said means comprising screw-rods journaled on the said bed and screwing in the said frame, a shaft geared with the said screw-rods, a second shaft geared with the first shaft, a driving mechanism for the second shaft, and means under the control of the operator, for adjusting the said driving mechanism, to rotate the screw-rods in either a forward or backward direction, to raise or lower the frame, as set forth.

2. A planer provided with a bed, a frame 25 vertically slideable thereon and carrying upper feed-rolls and a cutter-head, lower feed-rolls journaled in the said bed, a main shaft connected with the said cutter-head and the said lower feed-rolls, to rotate the same, means 30 for raising and lowering the said frame, the said means comprising screw-rods journaled on the said bed and screwing in the said frame, a driving-gear for rotating the said screw-rods from the said main shaft, and means under the control of the operator, for adjusting the said driving-gear, to rotate the screw-rods in either a forward or backward direction, to raise or lower the frame, the said means comprising a lever under the control of the operator, 35 a disk mounted to turn and connected with the said lever, and an arm mounted to swing and pivotally connected with the said disk, the said arm engaging the driving-shaft of the said gearing, for throwing the latter in engagement with oppositely-disposed driving gear-wheels, as set forth.

3. A planer provided with feed-rolls, mechanism for rotating the same forward and backward at a higher or lower rate of speed, a 40 driving-shaft geared with the feed-rolls and carrying a double-bevel gear-wheel, bevel-pinions in mesh with the said bevel gear-wheel, shafts carrying the said pinions, means under the control of the operator, for moving 45 the shafts toward and from each other, friction-pulleys on the said shafts, driven disks for engagement on their faces by the said friction-pulleys, and means under the control of the operator, for sliding the friction-pulleys on their shafts, to engage the friction-disks nearer to or farther from their centers, as set forth.

4. In a planer, the combination with a bed, and a vertically-adjustable frame carrying the

upper feed-rolls and the cutter, of screw-rods 65 mounted in the bed and screwing into the frame, a horizontal shaft geared with the screw-rods, a vertical shaft geared with the horizontal shaft and mounted at its lower end in a movable bearing, a second vertical shaft 70 geared with the first-named vertical shaft, and mounted in movable bearings, a gear on the lower end of each vertical shaft, a driven shaft provided with gears for engagement with the gears of the vertical shafts, and 75 means for moving the bearings of the vertical shafts, as and for the purpose set forth.

5. In a planer, the combination with a bed, and a vertically-movable frame carrying the upper feed-rolls and the cutter, of a horizontal shaft, means for raising and lowering the frame from said shaft, a vertical shaft geared with the horizontal shaft and provided with a friction-wheel at its lower end, a second vertical shaft 80 geared with the first-named vertical shaft and provided with a friction-wheel at its lower end, pivoted arms in which the vertical shafts are mounted, means for swinging said arms, a driven shaft, and three friction-wheels on the driven shaft, one of the 85 said wheels being a double-beveled wheel, as set forth.

6. In a planer, the combination with a driving-shaft, and feed-rolls, of three friction-disks on the driving-shaft, shafts extending 95 between the disks, pivoted arms in which the shafts are mounted, means for swinging the arms on their pivots, friction-pulleys slidably mounted on the shafts between the disks, means for sliding said pulleys, a shaft geared 100 with each of the said shafts, and means for operating one of the feed-rolls from said shaft, as set forth.

7. In a planer, the combination of a driving-shaft, feed-rolls, three friction-disks on the 105 shaft, shafts extending between the disks, pivoted arms in which the shafts are mounted, means for swinging the arms on their pivots, friction-pulleys slidably mounted on the shafts between the disks, means for sliding said pulleys, a shaft means for operating one of the fixed rolls from the said shaft, a double-bevel gear-wheel on said shaft, and a pinion on each of the shafts mounted in the swinging arms, as set forth.

8. In a planer, the combination with a bed, and a vertically-sliding frame on the bed carrying the upper feed-rolls and the cutter, of screw-rods engaging the frame, a horizontal shaft geared with the screw-rods, a vertical 110 shaft geared with the horizontal shaft and provided with a friction-wheel at its lower end, a second vertical shaft geared with the first-named vertical shaft and provided with a friction-wheel at its lower end, swinging 115 bearings for the said vertical shafts, means for swinging said bearings, a driven shaft, and friction-wheels mounted on the driven

shaft, and with which the friction-wheels of the vertical shafts engage, one of the said wheels being double, as set forth.

9. In a planer, the combination with a bed, and a sliding frame carrying the upper feed-rolls and cutter, of a vertical shaft, mechanism for raising and lowering the frame from said shaft, a second shaft geared with the first shaft, swinging arms in which the said shafts are mounted, means for swinging said arms,

a driven shaft, and gearing between the said shaft and the vertical shafts, as set forth.

In testimony whereof I have signed my name to this specification in the presence of two subscribing witnesses.

EDWARD RAWSON.
